ATTORNEYS.

UNITED STATES PATENT OFFICE.

FREDERICK W. WANNER, OF ST. LOUIS, MISSOURI.

PRICE MARKER.

Application filed October 13, 1927. Serial No. 225,936.

The invention relates to improvements in devices for marking goods with the prices asked therefor, and it aims to provide a new and improved article of this character in which a plate for holding either a one-piece price tag or price tag sections, is receivable together with the tag held thereby, in a spring clip on an attaching device for connecting plate and tag with the article on sale, the construction being such that the spring clip not only holds the price tag and its carrying plate upon the article on sale, but tenaciously holds the plate and the tag in proper relation with each other.

With the foregoing in view, the invention resides in the novel subject matter hereinafter described and claimed, the description being supplemented by the accompanying drawing.

Figs. 1 and 2 are front elevations of the invention showing tags arranged to denote different prices.

Fig. 3 is a detail vertical sectional view on line 3—3 of Fig. 1, one of the price tag sections being partially removed from the holding plate.

Fig. 4 is a front elevation of the tag holding plate.

Fig. 5 is a front elevation of one of the price tag sections.

Fig. 6 is a perspective view of the tag and plate attaching device.

The drawing above briefly described, illustrates the preferred form of construction and while this construction will be herein specifically explained, it is to be understood that within the scope of the invention as claimed, variations may be made.

The numeral 7 denotes a tag-holding plate of aluminum or other desired material said plate being provided at suitable points with tongues 8 preferably stamped therefrom and providing means for detachably holding a price tag, whether the latter be formed of one piece or of sections 9—9^a. This tag, whether formed of one or more pieces, is by preference constructed from celluloid with a numeral or numerals printed thereon to denote the price of an article upon which the tag is to be displayed.

An attaching device 10 is provided for the plate 7 and the price tag, said attaching de-

vice preferably consisting of a single length of wire bent to provide two attaching arms and a coil 11 connecting said arms, said coil constituting a spring clip. Into this clip, the 55 plate 7 and the price tag are forced, so that they may be held in proper position upon the produce or other goods on sale, and attention is invited to the fact that the clip 11 also tightly clamps the tag against the plate 7 to 60 prevent accidental disengagement of the two. When the tag is of sectional form as shown, the clip engages the abutting edges of said sections and thus holds the latter properly in 65 place.

The edge of the plate 7 to be engaged with the clip 11, is free of tag-holding means such as the tongues 8 and hence when said plate and the tag are disengaged from said clip, the tag or tag sections previously held by the plate 70 may be readily removed and replaced with others to denote a different price. Preferably, a two-section price tag is provided and by having tag sections on hand printed with all numerals, any two sections may be readily 75 engaged with the plate 7 to denote the desired price.

The arms of the attaching device are intended primarily to be forced into cuts of meat, but obviously an attaching device of 80 other form could be provided for connecting the plate and the price tag with other produce or the like on sale.

I claim:

1. A marker comprising a plate having 85 card-holding means at three edges but free of such means at its fourth edge, a card inserted into said card holding means from said fourth edge of said plate, and an attaching device having a spring clip jointly receiving 90 said fourth edge of said plate and the adjacent portion of said card, whereby to not only mount plate and card upon produce or the like on sale, but to removably hold the card engaged with said card-holding means. 95

2. In a marker, a plate having card-holding means at three edges but free of such means at its fourth edge to permit a card to be inserted from said fourth edge, and an attaching device having a spring clip to receive said 100 fourth edge and the contiguous portion of the card, whereby to not only mount card and

plate upon produce or the like on sale but to hold the card detachably engaged with said holding means.

3. A marker comprising a plate having card holding means at one edge but free of such means at its opposite edge, to permit a card to be inserted into said card holding means from said opposite edge and an attaching device having a spring slip to receive said

opposite edge of the plate and contiguous portion of the card, whereby to not only mount the card and plate upon produce or the like on sale, but to hold the card detachably engaged with said holding means.

In testimony whereof I have hereunto affixed my signature.

FREDERICK W. WANNER.
